ELECTRIC FITTING

Fred A. Reno, Gary, Ind.

Application February 8, 1935, Serial No. 5,540

3 Claims. (Cl. 200—87)

The present invention relates in general to an electrical fitting and is particularly concerned with an improved fitting of the type having a screw plug connection and a single two circuit socket or a pair of single circuit socket connections for receiving the screw base of an incandescent lamp, plugs etc.

More specifically, the fitting of this invention contains within its shell housing, an automatic switch which is connected in the circuit through the fitting in such a manner as to automatically disconnect the supply circuit from one of the socket circuits, when that socket circuit is interrupted, and connect the supply circuit to the other socket circuit.

The device or attachment of this invention is susceptible of myriad uses, and may, for example, be used to provide a main and auxiliary source of illumination by simply screwing an incandescent lamp into each of the double sockets or a two filament lamp into the double circuit socket type. When the main source of illumination or the main lamp is burned out or its circuit otherwise interrupted, the automatic switch therein automatically connects the auxiliary lamp into the circuit.

The fitting may also be utilized to energize a signal circuit, when the main circuit is interrupted. For example, the main circuit might feed the tail light of an automobile, a second light being provided in the circuit and mounted on the dash of the automobile so that when the tail light for any reason goes out, the signal light on the dash will be lighted. Similarly, the device is applicable to the operation of burglar alarms and other signal apparatus.

Although, the invention is primarily shown as being utilized in connection with incandescent lamps, it will be readily apparent to those skilled in the art that other current consuming devices may with equal facility be substituted for the incandescent lamps, depending upon the conditions under which the attachment is to be used.

It is a principal object of the invention to provide a self-contained electrical fitting embodying an automatic throw over switch, whereby upon the de-energization of a main circuit, an auxiliary circuit will be energized.

It is a further object of the invention to provide a fitting of the herein described character, which when not used in its particular capacity, may be utilized as the usual fitting of this type not having the throw over feature.

Other objects and features of this invention will more fully appear from the following detailed

description taken in connection with the accompanying drawing which illustrates several embodiments thereof, and in which:

Figure 1 is a large view of the fitting showing parts in elevation and having cutaway portions in sections to show the operative details of the associated instrumentalities thereof, this view showing a device adapted for use with a double filament incandescent lamp;

Figure 2 is a modified arrangement utilizing two outlet sockets instead of a single double circuit socket;

Figure 3 is a schematic diagram illustrating the electrical connections of the fitting;

Figure 4 is an enlarged view of the operating coil and the associated movable contact controlled thereby, portions of the coil being cut away to disclose details of construction; and

Figure 5 is a transverse cross section taken through the solenoid plunger of the operating mechanism.

As shown on the drawing:

In the form of the invention illustrated in Figure 1, the electrical fitting is disclosed as comprising a shell like structure 10 which is preferably constructed of an insulating material, and fitted at one end with a plug connection or base of the usual construction comprising a screw thread contact 11 and a central point contact 12.

At the lower end of the fitting, the shell 10 is formed to define a socket 13 in which there is mounted a screw thread sleeve 14 of the usual construction, this sleeve forming a contact into which the threaded base contact 15 of an incandescent lamp 16 may be screwed.

In this particular instance, the lamp 16 is of the two filament type comprising a main filament 17 and an auxiliary or secondary filament 18.

One end of each filament is connected to the screw base contact 15 and the other end of the main filament is connected to a centrally disposed and insulated contact pin 19, whereas the other end of the secondary or auxiliary filament is connected to the usual contact ring 20.

Electrical connections are made from the threaded base member 11 to the contact member 14 through a connection 21, which may be molded into the shell 10 as shown in the drawing or, if desired, may be carried through the interior hollow portion of the shell.

The base of the socket portion 13 of the shell is slightly contracted to define an annular shoulder 22 which serves as an abutment for an insulating member 23. This member serves as a support for contact members 24 and 25 which

are so disposed as to respectively cooperate with contact members 20 and 19 of the lamp base.

The insulating member 23 is formed with a pair of spaced leg portions 26 and 27 which cooperate to form a supporting bracket structure for a solenoid coil 28 having a hollow core construction for reciprocably receiving therein a solenoid 29. The member 23 and the legs 26 and 27 have portions in frictional engagement with the interior surface of the shell 10, whereby the solenoid and associated contacts are frictionally supported as a unit within the shell.

This solenoid is of tubular construction and along one side is provided with a longitudinally extending slot 30 for preventing flow of circulating or eddy currents which would cause the solenoid core to become heated. One end of the solenoid forms a solid extension 31 upon the outer end of which there is pivoted a disc shaped contact member 32. The disc is so mounted that it may be tilted as shown in dotted lines relative to its central pivot, thereby making the contact self-aligning. Normally, the contact 32 together with the solenoid is moved outwardly under the influence of a compression spring 33 having one end abutting the coil structure and its other end abutting the contact disc 32. It will be seen that this spring also tends to maintain the contact disc 32 in a position normal to its pivot.

The contact point 12 is connected by means of conducting members 34 and 35 to the contact 24. It will be observed that the free ends of these conductors are disposed immediately under the disc contact 32 so that when the disc 32 is moved downwardly under the influence of the spring 33, the circuit will be completed from contact point 12 to contact 24, but when the coil 28 is energized and the contact 32 is raised, this circuit will be interrupted.

One end of the coil 28 is connected to conductor 34 and the other end of the coil is connected to contact 25.

From the foregoing description, it will be seen that when the main filament 17 is energized, the coil 28 which is in series with the main filament, will also be energized to open the circuit through conductors 34 and 35 to contact 24 which is in circuit with the main or primary filament. Should the main filament, however, be burned out for any reason, the coil 28 will be de-energized and the spring 33 will force contact 32 into engagement with the free ends of conductors 34 and 35 and immediately connect the auxiliary or secondary filament 18 into the circuit.

Figure 2 shows a modified arrangement wherein the shell structure is formed to define angularly disposed single circuit sockets for respectively receiving a single filament lamp 36 and plug connector 37, instead of a single double circuit socket as shown in Figure 1.

In the modified form, corresponding numbers have been used to indicate parts corresponding to those shown in Figure 1.

The plug connector 37 may be utilized for making circuit connections to remotely located lamps or other electrical devices of a current consuming nature, or, if desired, an auxiliary lamp may be inserted in the socket in place of the plug 37.

In this form of the invention, the coil 28 is supported on a bracket such as shown at 38, and it will be observed that the screw socket contacts 14 and 14' are interconnected by a conductor 39.

In both the preferred and modified forms, the

plug and socket connections are disclosed as being of the screw type. It is contemplated, however, that any of the various and well-known types of connection such as bayonet connections and others may be used.

Referring to Figure 3, the electrical connections between the various parts of the invention are shown. It will be observed that the invention may be utilized to control a main source of illumination such as an incandescent lamp 36 and an auxiliary source of illumination such as an incandescent lamp 36'. The lamps 36 and 36' are connected in parallel across an electrical circuit 40. In series with the main lamp 36 is the operating coil 28 of the switch mechanism. The movable contact 32 is arranged to close the parallel circuit through the auxiliary lamp 36' when the coil 28 is deenergized by a burning out of the main lamp 36 or otherwise opening its circuit. When the circuit through the coil 28 is deenergized, the spring 33 moves the contact 32 into closed cooperation with the associated contacts in the parallel circuit of auxiliary lamp 36'. The auxiliary lamp is thereupon lighted, the source of supply being from the electrical circuit 40.

From the foregoing description, it will be apparent that this invention provides a novel electric fitting which embodies an automatic switch for automatically transferring the supply circuit 30 to an auxiliary circuit, when the main circuit is interrupted; a fitting which, when it is not used for the special purpose for which it is adapted, may be used in the same manner as the usual fitting of this type; and a fitting which is 35 adapted for use in signal circuits and a great number of different arrangements, wherein it is desired to quickly and easily provide an arrangement for connecting a supply circuit either to a main outlet or an auxiliary outlet, when the main 40 outlet circuit is interrupted, without the necessity of expensive and special wiring.

Now, of course, it is to be understood that while the invention is illustrated and described in detail in a preferred and modified form, the invention is not to be thus limited but only insofar as defined by the scope and spirit of the appended claims.

I claim as my invention:

1. As an article of manufacture, an electrical fitting having a single circuit inlet connection and double circuit outlet connections; said fitting comprising a main elongated shell portion of substantially tubular construction, an inwardly extending abutment shoulder formed on the interior surface of the shell, a disk of insulating material abutting the shoulder and held in position by the engagement of its periphery with the interior of the shell, a solenoid coil within the shell connected in series in one of the outlet circuits, a pair of coil supporting brackets carried by said disk, a pair of spaced contacts connected in series in the other outlet circuit, a solenoid core operatively associated with said coil, a contact carried by said core adapted to bridge the spaced contacts, when the coil is de-energized, and open the circuit through the spaced contacts, when the coil is energized, and spring means for moving the core in a direction to bring the bridging contact into bridging position, when the coil is de-energized.

2. As an article of manufacture, an electrical fitting having a single circuit inlet connection and double circuit outlet connections; said fitting comprising a main elongated shell portion of sub-

stantially tubular construction, an inwardly extending abutment shoulder formed on the interior surface of the shell, a disk of insulating material abutting the shoulder and held in position by 5 the engagement of its periphery with the interior of the shell, a solenoid coil within the shell connected in series in one of the outlet circuits, a pair of coil supporting brackets carried by said disk, said brackets making frictional engagement 10 with the interior of the shell to augment the holding action of the disk, a pair of spaced contacts connected in series in the other outlet circuit, a solenoid core operatively associated with said coil, a contact carried by said core adapted 15 to bridge the spaced contacts, when the coil is de-energized, and open the circuit through the spaced contacts, when the coil is energized and

spring means for moving the core in a direction to bring the bridging contact into bridging position, when the coil is de-energized.

3. As an article of manufacture, an electrical fitting having a single circuit inlet connection and 5 double circuit outlet connections; said fitting comprising a tubular shell having an internal shoulder adjacent one end, an insulating disk abutting said shoulder, switch means supported on said disk for automatically connecting the 10 inlet circuit to one of the outlet circuits, when the other of the outlet circuits is de-energized, and terminal contacts carried by said disk disposed for engagement by the contacts of a power consuming device to be connected to said circuit. 15
